UNITED STATES PATENT OFFICE.

JOHN J. MC LAUGHLIN, OF TORONTO, CANADA.

DESIGN FOR A HOLDER FOR SODA-WATER GLASSES.

SPECIFICATION forming part of Design No. 34,621, dated June 4, 1901.

Application filed May 6, 1901. Serial No. 59,059. Term of patent 7 years.

To all whom it may concern:

Be it known that I, JOHN J. MC LAUGHLIN, a subject of the King of Great Britain, residing at the city of Toronto, in the county of York, 5 Province of Ontario, Canada, have invented and produced a new and original Design for a Holder for Soda-Water Glasses, of which the following is a specification, reference being had to the accompanying drawings, forming part thereof.

Figure 1 is a vertical sectional elevation of my holder. Fig. 2 is a perspective view of the same.

As shown in the drawings, the holder comprises a base A, formed with a hollow rim B, forming a drip-pan. The rim of the base flares outwardly and upwardly from the bottom C with an ogee curve, as seen in Fig. 1.

It is then bent inwardly and downwardly to form the flange D. To the inner edge of this

flange are connected standards E, which carry the ring F, within which the glass is inserted. The handle G is connected to the holder in line with one of the standards.

The chief novelty of the design lies in the 25 shape of the base with its flaring rim and inwardly and downwardly projecting flange; with the standards rising therefrom.

Having described my invention, what I claim as new, and desire to secure by Letters 30 Patent, is—

The design for a holder for soda-water glasses, as herein shown and described.

In testimony whereof I have signed my name to this specification in the presence of 35 two subscribing witnesses.

JOHN J. MC LAUGHLIN.
